UNITED STATES PATENT OFFICE

GERHARD WAGNER, FRIEDRICH FUNKE, AND RUDOLF HEYMANNS, OF DUSSELDORF,
OBERKASSEL, GERMANY

ADJUSTABLE TIGHTENING DEVICE FOR DOORS AND THE LIKE

Application filed February 24, 1927, Serial No. 170,634. Renewed January 24, 1930.

Our invention refers to an adjustable means for tightening doors or the like.

The accompanying drawings illustrate an embodiment of the invention.

Fig. 1 shows the device mounted and ready for use, and the tightening lath, as shown, drawn up by a spring bolt;

Fig. 2 shows the same device having its tightening lath pushed down;

Fig. 3 shows on an enlarged scale the adjusting mechanism with sliding socket;

Fig. 4 shows the device within the socket, fitted through a fillet on the door;

Fig. 5 shows a cross section of the device on line 5—5 of Figure 2, the device being mounted in a door previously slit.

Figures 6 and 7 are views illustrating the operation of the device.

In a groove or in a slit guide (a) of a well known kind, there is guided the rod (b) which is embedded in the board (c) of the door (d) and which is retracted by means of the spring (b¹).

The rod (b) guided as above stated, has on its front portion threads (f) over which a socket (g) or the like is screwed. The socket (g) is so shaped that it will project beyond the lath (c) of door (d).

Underneath the rod (b) there is the sliding lath (i) with the fitting (s) and the tightening material (k).

Said sliding lath (i) is connected with the rod (b) by means of the articulated arm (m). One lever of the same has also a lever-arm (n) which is connected with the lath (c).

Now when the door (d) is being closed and when the socket (g) is screwed onward, the stop will push against the door frame (h) and the rod (b) will slide or push back the upper levers (m) with their upper ends.

Now as the levers (m) are supported by the likewise oscillating lever (n), the lower ends of the levers (m) will be positively pushed downwards, so that when the door is being closed the sliding lath (i) with its tightening material (k) will be pushed downwards. The

more the levers (m) are in a horizontal posi-

tion, the more will the tightening material (k) be pushed down in a substantially vertical direction. By adjusting socket (g) on the threaded end of the rod (b) the degree of movement of the lath (i) may be regulated.

The spring (b¹) will push the rod (b) back to a certain extent, after the door has been opened again, so that the sliding lath (i) with its tightening brim (k) will be moved up by means of the supported lever (m).

As the lath (i) strikes against the rod (b) or against another stop, the rod (b) comes to a standstill in spite of the spring (b¹) acting upon it.

It will be possible to screw in the socket (g) entirely, without the door striking against it and it will be possible also to set

the tightening mechanism, partially or wholly, out of function, which would not be possible if there were no adjustable stop arrangement on the upper tightening lath (i).

The whole device is fastened to an iron strip (o), so that, when this iron strip is screwed to the door or the like, the whole mechanism will be fastened.

When providing or arranging another iron strip with an intermediate distance strip, it is possible to fix the whole device to a door having no wash-board (see Figure 5).

In this case there will be instead of one iron strip, one strip at the right hand side and one at the left hand side and the whole device will be inserted

into the door slot (p) and will be easily fastened by means of screws.

We claim:

1. In combination, a closure strip, a carrier therefor, and means for moving said strip, comprising a stationary support, a reciprocating rod, levers connected at their ends to said rod and to said carrier, and links connected to support and to said levers intermediate the ends thereof, whereby movement of said rod in one direction causes said carrier and closure strip to move in a direction at right angles thereto.

2. In combination, a closure strip, a car-

rier therefor, shoes secured to said carrier, a supporting member, a reciprocating rod, levers connected at their ends to said rod and to said shoes, and links connected to said supporting member and to said levers intermediate the ends thereof whereby movement of said rod in one direction causes said levers to move said carrier in a direction at right angles thereto.

10 In testimony whereof we affix our signatures.

GERHARD WAGNER.
FRIEDRICH FUNKE.
RUDOLF HEYMANNS.
